[57] CLAIM

The ornamental design for a flat bread maker and spatula, as shown and described.

DESCRIPTION

FIG. 1 is a perspective view as seen from the top, front, and left side of a flat bread maker and spatula showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view similar to FIG. 1 but with the upper platen handle in its downward, engagement position;

FIG. 9 is a perspective view as seen from the top, front, and left side of the spatula of the flat bread maker, shown separately for ease of illustration;

FIG. 10 is a left side elevational view thereof, the right side being a mirror image of the left side;

FIG. 11 is a front elevational view thereof;

FIG. 12 is a rear elevational view thereof;

FIG. 13 is a top plan view thereof; and,

FIG. 14 is a bottom plan view thereof.

The broken lines in FIGS. 1 through 5, 7, and 8 showing the power cord, the feet, and the underside plate and vents are used for illustrative purposes only and form no part of the claimed design.
